Primary Examiner—Pamela Burgess**[57] CLAIM**

I claim the ornamental design for a telephone enclosure, as shown.

DESCRIPTION

FIG. 1 is a front perspective view of a telephone enclosure showing my new design;

FIG. 2 is a front elevational view thereof;

FIG. 3 is a top plan view thereof;

FIG. 4 is a right side elevational view thereof;

FIG. 5 is a rear elevational view thereof;

FIG. 6 is a left side elevational view thereof; and,

FIG. 7 is a bottom plan view thereof.
